UNITED STATES PATENT OFFICE.

LEON COHEN, OF ST. LOUIS, MISSOURI.

HAT-SIZE REDUCER.

Application filed March 31, 1924. Serial No. 703,292.

My invention relates to improvements in hat size reducers and has for its primary object a device whereby the size of a hat can be readily reduced so as to fit various sizes 5 of heads and which can be readily attached and detached from a hat.

A further object is to construct a hat size reducer which can be cheaply constructed, readily placed in position within a hat and 10 make the front part of the hat fit snugly against the forehead so as to prevent any unsightly spacing between the forehead and the hat.

A still further object is to construct a hat 15 size reducer which when readily reducing the size of the hat will do so in a manner as not to pinch or bind the hat uncomfortably against the head, and which will readily adjust itself to various sizes of heads within 20 certain limits.

In the drawings:

Fig. 1 is a plan view of my device before being inserted into a hat;

Fig. 2 is an edge view of the same viewed 25 in the direction of the arrow 2;

Fig. 3 is a plan view of my device showing the same in position with a fragmental portion of a hat crown shown in section;

Fig. 4 is an enlarged section taken on the 30 line 4—4 of Fig. 1;

Fig. 5 is a plan view showing the manner of assembling the resilient and the flexible members and before the covering is applied thereto; and

Fig. 6 is a plan view of a modified form 35 wherein the covering is omitted.

In carrying out my invention I employ a resilient strip 7. This strip is preferably of 40 spring metal and is provided adjacent each end with prongs 8. These prongs may be either integral with the member or attached thereto in any well known manner. The member 7 is also provided with prongs 9 which may vary in number and which are 45 constructed in the same manner as the prongs 8, in other words, they may be either formed integral with the member 7 or attached thereto.

Secured to the member 7 is an elastic 10, 50 this elastic may be either webbing or a cord, the webbing however, being preferable as it can be more readily attached. This elastic is of less length than the member 7 so that when the ends of the elastic are attached, 55 which is preferably done by inserting the

prongs 8 therethrough, the member 7 will assume the bow shape as shown in Fig. 5.

The member 7 together with the prongs and the elastic 10 are then inserted in a crescent shaped covering 11 which is preferably 60 formed of fabric. This covering is left open at one end until the members 7 and 10 have been inserted and the prongs 8 and 9 forced therethrough as shown in Figs. 1 and 3, and the open end then closed either by sewing 65 or gluing. The member will then have the appearance of a crescent with the prongs projecting from the convex surface thereof.

It is to be noted in this connection that 70 the radius of the circle of the convex portion must be of greater diameter than the radius of the interior of the hat crown so that the ends of the crescent must be sprung together while the device is being placed in position and the prongs pushed through the 75 material 12 of which the hat crown is made. The resiliency of the member 7 then holds the device in position. When the device has been placed in position the convex surface 13 of the reducer conforms with the interior of 80 the hat crown, while the concave surface 14 of the elastic 10 extends across a portion of the hat crown in the arc of a larger circle thus reducing the size of the hat, and when the same is placed on the head the elastic 85 will stretch and permit the hat to fit snugly, or when placed in the rear of the crown will draw the forward part of the hat against the forehead of the wearer.

In Fig. 6 I have shown a modified form 90 in which the fabric covering 11 is omitted, but in this instance, a cord 15 is employed to draw the center part of the elastic 10 inwardly so that it will not extend as a chord 95 across the bow formed by the member 7. When used in this manner, the device in addition to being a hat size reducer, will also 100 act as a ventilator and permit the circulation of air underneath the hat crown. The cost of construction is also reduced in the modification because the additional labor and material necessary to construct the covering 11 is eliminated.

The essential feature of my device is the 105 curvature of the member 7 and the construction of it out of resilient material because as long as the curvature is of a radius greater than the radius of the curvature of the hat crown the tension set up in the member 7 in placing it within a hat crown will hold 110

it in position. This feature makes it unnecessary to sew or pin the device within the hat and consequently makes it readily interchangeable with numerous hats.

5 Having fully described my invention, what I claim is:—

1. A hat size reducer comprising a crescent shaped cover, a flexible strip of spring material located within said cover and along 10 the convex edge thereof, prongs carried by said strip and projecting from the convex edge and at an angle thereto and through said cover, an elastic strip located within said cover along its concave edge, said elastic strip having its ends secured to the ends of the flexible strip, the radius of curvature of the convex edge being greater than the radius of curvature of a hat crown, whereby 15 the tension set up in the flexible member 20 when the device is placed within a hat will hold the prongs in engagement with the hat crown.

2. A hat size reducer comprising a strip of flexible material having securing prongs 25 carried by and projecting from one face thereof, a strip of elastic of less length than the flexible strip, said strip of elastic having its ends secured to certain of said prongs adjacent the ends of the flexible strip where- 30 by the latter is bowed outward from said elastic strip, and means for drawing and holding said elastic strip intermediate its ends toward the flexible strip without caus- 35 ing it to contact with said flexible strip.

3. A hat size reducer comprising a strip of flexible spring material having prongs secured to and from one face thereof, an elastic strip of less length than the flexible strip, said strip having its ends secured to 40 the ends of the flexible strip whereby the latter is bowed outward from said elastic strip, and a flexible crescent shaped cover surrounding said flexible and elastic strips, said flexible covering having the prongs 45 carried by the flexible strip projecting through the convex edge thereof, said prongs adapted to be forced into the material out of which a hat crown is constructed and be held therein by tension set up in the 50 flexible member when the device is placed in position.

4. A hat size reducer comprising a bow-shaped member having prongs projecting outwardly from its convex surface, an elastic member secured to said bow-shaped member 55 at its ends only, said elastic member having the major portion thereof located between the ends of the bow-shaped member and ex- tending across the concave surface thereof 60 in such a manner that the portion of the elastic material between the ends of the bow- shaped member does not contact therewith.

5. A hat size reducer comprising a flat

strip of spring material of less length than the interior circumference of a hat crown, 65 a plurality of spaced apart prongs carried by said strip and extending at right angles thereto for holding the same in conformed relation to the inside of said hat crown, a piece of fabric encased yielding material 70 carried by the flexible strip and secured adjacent the ends thereof and having a major portion thereof extending inwardly from the periphery of said hat crown so as to reduce the head receiving opening. 75

6. A hat size reducer comprising a flat strip of spring metal, a plurality of spaced apart prongs carried thereby, at least one of which projects at right angles from the rear surface thereof, a piece of fabric encased 80 elastic material carried by said flexible strip and located opposite the face from the projecting prong and extending inwardly from the periphery of the hat crown so as to reduce the size of the head receiving opening 85 thereof.

7. A hat size reducer comprising a flat strip of spring metal, a plurality of securing prongs carried by said strip, at least one of which is intermediate the ends and extends 90 substantially at right angles to said strip, a piece of elastic material of less length than the flat strip, said elastic material having its ends secured to said strip adjacent its ends whereby said strip is bowed outwardly from the elastic with the prong on 95 its convex surface, said strip adapted to be secured within a hat crown so that the elastic will extend across a portion of the head receiving opening and reduce the size 100 thereof.

8. A hat size reducer comprising a relatively short flexible strip, prongs carried by said strip and projecting from one face thereof, a fabric covering surrounding said 105 strip and held in position thereon by passing said prongs therethrough, and an elastic strip located in said covering adjacent the face of said flexible strip opposite that from which said prongs project. 110

9. A hat size reducer comprising a relatively short flexible strip arcuate in form when in use, prongs carried by said strip and projecting from the convex surface thereof for securing said strip within the 115 head receiving opening of a hat crown, a fabric covering surrounding said strip, said covering having the prongs passing therethrough whereby said covering is held against shifting, and an elastic strip located 120 within said covering adjacent the concave face of the flexible strip.

In testimony whereof, I have signed my name to this specification.

LEON COHEN.
